ALEXANDER MCLEAN NICOLSON, OF NEW YORK, N. Y., ASSIGNOR, BY MESNE ASSIGNMENTS, TO FEDERAL TELEGRAPH COMPANY, A CORPORATION OF CALIFORNIA

PIEZO-ELECTRIC-CRYSTAL STABILIZER MODULATOR

Application filed January 18, 1927. Serial No. 161,853.

This invention relates to apparatus for producing electrical oscillations of relatively high frequency, suitable for "carrier current" or radio transmission, modulated at relatively

lower frequencies and, more particularly, to of a frequency suitable for "carrier current" or radio transmission, such, for example, as an oscillator, preferably a thermionic vacuum tube oscillator.

I also provide a pair of crystal devices, 55 one of which is particularly adapted to respond to the frequency desired for transmission for the purpose of controlling and stabilizing the same, and the other of which is adapted to respond to acoustic vibrations 60 and to convert the same into electric oscillations corresponding thereto, which may be used to modulate the high frequency oscillations. Both of these crystal devices are arranged in circuit in such manner as to control 65 the potential between the grid and filament of a thermionic amplifier, which produces in its output circuit the high frequency signalling oscillations modulated at the low frequencies of the signal, whether these low 70 frequencies be speech, music or other audible signals.

The modulated high frequency oscillations may then be passed through a suitable power amplifier and amplified to the desired extent, 75 after which they may be impressed upon the load circuit such for example, as an antenna or a wire line.

According to another, and in some instances preferred, form or modification of my invention, I may dispense with the separate oscillator and provide an arrangement of circuits associated with the amplifier, such that this amplifier itself acts as a generator of high frequency oscillations, the frequency of 85 which is stabilized by one of the piezo-electric crystal devices. The oscillations of modulating frequency or frequencies, are supplied by the other or low frequency piezo-electric device. In this instance, although only a 90 single amplifying system is utilized, the currents flowing in the output circuit thereof are similar to those produced by the apparatus shown in Fig. 1, and these currents may therefore be supplied to a power amplifier and 95 amplified to the extent desired for impression upon a load circuit such as an antenna or a wire line.

Referring now more particularly to Fig. 1, 1 designates a piezo-electric crystal device of 100

5 lower frequencies and, more particularly, to such apparatus, utilizing piezo-electric crystal devices for introducing the control or stabilization of the high frequency, and also for introducing the modulating frequencies.

10 It is an object of this invention to provide apparatus of the class described utilizing a piezo-electric device particularly adapted for stabilizing the high frequency, and an additional piezo-electric device particularly

15 adapted for the introduction of the low or modulating frequencies into the system.

It is a further object of this invention to provide apparatus of the class described utilizing the minimum number of vacuum 20 tube amplifiers and performing simultaneously the functions of oscillation generation, frequency stabilization, and modulation by means of a single amplifying system, and utilizing for the high frequency control a 25 piezo-electric crystal device particularly adapted thereto, and for the low frequency oscillations a piezo-electric crystal device particularly adapted thereto.

It is still a further object of this invention 30 to provide such apparatus in which the various crystal devices are arranged so as not to interfere with each other in operation at widely different frequencies in the same circuit.

35 Still other objects of this invention will be apparent from the specification.

The features of novelty which I believe to be characteristic of my invention, are set forth with particularity in the appended claims.

40 My invention itself, however, both as to its fundamental principles and as to its practical applications, will best be understood by reference to the specification and accompanying drawing, in which:

45 Fig. 1 is a diagrammatic view of one form of apparatus according to my invention.

Fig. 2 is a similar view of another form thereof.

In accordance with my invention, I provide 50 an apparatus for producing oscillations

high dielectric constant, such for example as a crystal of Rochelle salt exhibiting the "hour glass" configuration as described in my paper entitled "Piezo-electric effect" delivered before the American Institute of Electrical Engineers, on Oct. 9, 1919, and provided with electrodes 2 and 3 at opposite electrical poles and also provided with mounting plates 4 and 5 if desired. An acoustic diaphragm such as a cone 6 may be attached to a mechanical pole of the crystal device, in such manner as to cause vibration of the crystal and generation of corresponding electrical oscillations when sound vibrations strike the cone.

A second piezo-electric crystal device 7, such for example as a quartz crystal, having its shape and dimensions so chosen as to be resonant to the high frequency which it is desired to transmit, is also provided, having electrodes 8 and 9 at the proper points, as known in the art. In this instance, a coil 10 may be provided inductively coupled to a second coil 11, one end of which second coil 25 may be connected to the grid or control electrode 13 of a thermionic amplifier 12. The opposite end of the coil 11 may be connected through a suitable source of potential 17 to the anode 14 of the said amplifier, and the cathode 15, energized by a suitable source of potential such as battery 16, is connected to an intermediate point upon the coil 11. This arrangement forms what is known as a "feed back circuit," well known in the art, which 35 may be adjusted to produce oscillations of substantially the desired frequency.

A connection may be made between electrode 8 of crystal device 7 and electrode 3 of crystal device 1, and connections also established from electrode 2 of crystal device 1 to the control electrode or grid 21, of thermionic vacuum tube amplifying system, shown diagrammatically as a single tube; also, a connection may be made from electrode 9 to one end of coil 10, the other end of which may be connected to the cathode 23 of the amplifier 20, which cathode may be energized by a suitable source of potential such as battery 24. The anode 22 of the amplifier 20 may be connected through coil 26 and a source of potential 25 to the cathode circuit.

A second coil 27 inductively coupled to coil 26, so as to form a transformer, may be connected to the input circuit of a suitable power amplifier, containing as many stages as may be required to increase the power output to the level desired. The output circuit of the power amplifier may include a coil 29 coupled to a load circuit such as an antenna, in any suitable manner, such as by inductive coupling to an additional coil 30 connected in the load circuit. If now the various amplifiers be set into operation and the circuits as described, it will be found that the high frequency oscillations produced by amplifier 12

will be stabilized by piezo-electric crystal device 7, and thereby held to a very constant value.

Electrical oscillations corresponding to sounds such as speech and music directed against the acoustic device such as cone 6, will be produced by crystal device 1, and superimposed upon the high frequency oscillations supplied to grid 21, the result of which will be that in the output circuit of the amplifier 20, will be found high frequency oscillations of very constant frequency, modulated by the low frequency oscillations corresponding to the sounds striking the diaphragm 6. By means of the power amplifier 28, these oscillations may be amplified to the extend desired without serious deformation or distortion, and may thereafter be supplied to a load circuit such for example as an antenna.

Referring now more particularly to Fig. 2, I have shown a modified form in which I dispense with the separate oscillator 12, and its associated circuits, by arranging to have the amplifier 20 act as an oscillator. In this instance coil 40 may be provided in the output circuit of the amplifier 20, and an additional electrode 41 may be provided on the crystal device 7.

One end of coil 40 may be connected through the source of potential 25 to the anode 22 of tube 20: the other end of this coil will be connected to the cathode and to one of the electrodes of the crystal device, as for example electrode 41. A connection will also be provided from an intermediate point on coil 40 to another electrode of the crystal device 7, as for example electrode 8. A third electrode 9 may then be connected to electrode 3 of crystal device 1, electrode 2 of which will be connected as before to the control electrode 21 of the amplifier 20.

Under these conditions, by proper adjustment of the apparatus, it will be found that the currents flowing from the output 40 through the crystal device 7 to the cathode cause mechanical and electrical vibrations of this device at its natural frequency, resulting in the production of an electromotive force between the electrodes 41 and 9, which is impressed upon the control electrode, whereby sustained oscillations of desired frequency are produced in the output circuit of amplifier 20. These oscillations will be modulated as before, through the action of crystal device 1 in response to acoustic vibrations impressed upon cone 6: and may be amplified by a suitable power amplifier to the extent desired before being supplied to the load.

Since the capacitive impedance of crystal device 1 to frequencies of the order of those desired for transmission is relatively low, it is not necessary to provide a by-pass for these high frequency oscillations around this crystal device. On the other hand, however, the impedance of the crystal device 7 to relatively

low frequencies corresponding to speech and music, is usually relatively high, and for the best results, it may be desired to provide a shunt path for low frequency currents around this crystal, which may be formed by the connection of a suitable coil 42 between electrodes 8 and 9, in the first instance, and electrodes 9 and 41 in the second. This coil, as will be understood, should have sufficient inductance to act as a choke to the high frequencies produced by the crystal device 7, but as a path of low impedance to the low frequencies produced by the crystal device 1.

The piezo-electric crystal devices herein diagrammatically shown may comprise devices of any suitable material, size, shape, and arrangement known in the art and suitable for the purpose, and may for example comprise arrangements described and claimed 20 in my copending applications

impedance to oscillations of audio frequency. 3. In combination, an electron discharge device having an anode, a cathode and a control electrode, input and output circuits interconnecting said electrodes, sources of potential for said electrodes, means for generating electrical oscillations in said input circuit, a piezo electric device responsive to mechanical vibrations, means for impressing sound waves thereon, a second piezo electric device resonant at the frequency of said oscillations, said piezo electric devices being connected in series in said input circuit, and an inductance shunted across the second named piezo electric device. 70 75

In testimony whereof I hereunto affix my signature. 80

ALEXANDER McLEAN NICOLSON.

35 While I have shown and described certain preferred embodiments of my invention, it will be understood that modifications and changes may be made without departing from the spirit and scope of my invention, as 40 will be understood by those skilled in the art.

I claim:

1. In combination, an electrical circuit, means for setting up electrical oscillations therein, a piezo electric device in said circuit 45 adapted to control the frequency of said oscillations, another piezo electric device in said circuit, and means for mechanically vibrating the second named piezo electric device, said second named piezo electric device being 50 adapted to modulate said oscillations in accordance with the mechanical vibrations.

2. In an oscillatory circuit, the combination of a piezo electric device adapted to change its electrical characteristics in accordance with mechanical vibrations of audio frequency, a second piezo electric device adapted to resonate at a super-audible frequency and thereby to control the frequency of the oscillations in said circuit, and an inductance connected in parallel with said second named piezo electric device wherein the first named piezo electric device offers a low impedance to said super-audible oscillations and said inductance offers a high impedance 65 to said super-audible oscillations and a low
